UNITED STATES PATENT OFFICE.

JUAN MUGICA, OF SAN SABASTIAN, SPAIN.

ROAD-PAVING APPARATUS.

1,263,272.

Specification of Letters Patent. Patented Apr. 16, 1918.

Application filed July 9, 1914. Serial No. 850,064.

To all whom it may concern:

Be it known that I, JUAN MUGICA, a subject of the King of Spain, and residing at No. 9 Calle Miracruz, San Sebastian, Spain, 5 have invented a certain new and useful Road-Paving Apparatus, of which the following is a specification.

The present invention has for its object to facilitate the paving of roads, court-yards 10 or the like with asphalt or asphalt substitute more particularly in countries where the said material is cheap.

The essential features of the present invention is a machine, either stationary or 15 portable which enables the manufacturing of strips or slabs of compressed asphalt or the like material, reinforced or non-reinforced with iron wire, rope, catgut or the like of any length or width desired, the 20 strips or slabs being of large surface whereby the paving can be done more rapidly, better and at a lower cost than is the case with the old processes employed.

The output of the said new machine or 25 press is several times greater than that of any other press known and its running costs very small, thus enabling the above described paving material to be produced at a comparatively very low price.

30 This new paving has the same advantage as that obtained with the commonly used small sized compressed squares or slabs, since the strip of asphalt may be made of any desired strength or hardness by subjecting it to a pressure, recognized in practice, as suitable and varying from 400 to 1000 kilograms per square centimeter, or more, and moreover, it has the advantage of constituting large monoliths and of obviating 35 a needless number of pieces and joints.

The strips or slabs may vary in width 40 from one to several yards, according to the width of the compressing mold. The length of the strips depends upon the requirements, 45 since the production of the strip of asphalt is continuous and is only stopped intentionally or by reason of an accident.

The reinforcement is disposed lengthwise and crosswise, since its main object resides 50 in preventing breakage, which, on placing the strip of slabs of asphalt in position, may occur in the strip or slabs by rough manipulation thereof, the use of this reinforcement, in certain cases, may be dispensed 55 with, especially that in transverse direction,

and sometimes also in longitudinal direction.

To position the reinforced strips or slabs of compressed asphalt, it is sufficient to prepare a bed of concrete upon which the said 60 strips or slabs are set in position and if more adhesion between the strips or slabs and the concrete bed is preferred, this may be spread over with a thin coating of fluid cement mortar before positioning the strip 65 or slab.

To this end and in accordance with the invention, a machine or press as hereinafter described and illustrated in the accompanying drawings is provided and constructed. 70

Figure 1 is an elevation of the more important side of the apparatus.

Fig. 2 is an elevation of the other side;

Fig. 3 is a plan view on section line A—B;

Fig. 4 is a vertical and longitudinal section on the line C—D. 75

Fig. 5 is a side elevation of the compression mold, which constitutes the essential part of the machine or press; it also shows in detail other parts of the mechanism of 80 said machine.

Fig. 6 is a vertical and longitudinal section of the same mold taken on the line C—D of Fig. 3;

Fig. 7 is a section of one half of the mold 85 on the line E—F and

Fig. 8 is a section of one half of the mold, taken on the line G—H.

Fig. 9 is a straight flat iron bar for cutting the strips of asphalt. 90

Figs. 5, 6, 7 and 8 show in detail the essential and fundamental parts of the mechanism; the remainder of the mechanism being subject to modifications which do not influence the fundamental principle of the 95 invention.

The machine or press comprises the following parts:

A strong iron frame 1 which carries at one end an electric motor 2, which by means 100 of gearing transmits its movement to shaft 3 which, in its turn does the same to the crank shaft 4, as shown in Figs. 1 and 3.

The crank shaft 4 which, by means of the connecting rods 5 imparts a reciprocating 105 movement to the carriage 6, as shown in Figs. 3 and 4.

A compressing piston 7 is firmly fixed to the above carriage by means of bolts.

The bottom plate or base 8 of the com- 110

pressing mold, constitutes the bottom and side walls or faces of the compression mold and has a face plate 8^a which can be interchanged when worn down.

5 The top or cover plate 9 of the mold is firmly secured to the bottom plate by the screw bolts O.

The rocking plate 10, contained in said top or cover plate constitutes the top wall 10 or face of the compression mold, the front edge of which is beveled at b as shown in Fig. 6.

The distance pieces 11 may be adjusted between the plates 8 and 9 for varying the 15 distance between the rocking plate and the bottom plate or base of the mold.

The screws 12 are for varying the inclination of the rocking plate with regard to the bottom plate or base of the mold.

20 The shaft 13 is by means of a pulley 13^a and belt 72 directly set in motion by the motor 2, as shown in Figs. 1, 2 and 3.

The friction pulleys 14 and 15 which are alternatively set in motion by contact with 25 the pulley 13^a which is fixed on to the opposite end of the shaft 13 as shown in Fig. 1.

The plate 16, is suspended from shaft 18 and is controlled by lever 20; said plate carries the friction pulleys 14 and 15 which 30 by means of pinions work the toothed wheel 17 which, in its turn and by means of the shaft 18 and its endless screws 18^a drives the gear wheels 19, which gear wheels are firmly fixed to and work the screws 12 as 35 shown in Fig. 5.

21 is a hopper at the bottom of which is placed the grooved cylinder 22 for distributing or feeding asphalt powder or the like material, which cylinder is mounted upon 40 the shaft 23 and rotated by the ratchet wheel 24 and pawl 24^a pivoted on an arm which is operated by a rod 25 connected to the bell crank arm 26 which bell crank is actuated by the rotating arm 27 fixed to 45 the end of the crank shaft 4, and by the spring in dashpot 28.

The shaft is fitted with blades 22^a, the rotation of which is combined with that of the feeding cylinder 22 by means of the gear 50 wheels 58 and 59. The blades engage in the grooves of the distributing or feeding cylinder 22, thereby removing the asphalt powder from said grooves.

The toothed lever 29 is provided for limiting the course of the ratchet wheel 24 and pawl 24^a said lever being fixed to one end of the shaft 24^b to the other end of which is fixed the stop arm 29^a, as shown in Figs. 1 and 2.

60 The transverse wire magazine 31 with its wire distributor 32 is driven by lever and pawl 33 which lever is actuated by an inclined plane 34 fixed on the reciprocating carriage 6, as shown in Figs. 1 to 4.

65 The longitudinal iron wire magazine or

carrier 35 carries the rolls of wire the ends of which are passed under the guiding pulleys 36 and over the pulleys 37, under the piston guide 38 and through wire guiding channels ending in holes with which the 70 compressing piston 7 is provided, into the compression mold, as shown in Figs. 1, 2 and 6. Said wires, constituting the longitudinal reinforcement of the compressed strip or slabs produced, may be substituted 75 by a rope, catgut or the like.

The plate or blade 39 is, for flattening the asphalt powder delivered by the grooves of the feeding cylinder, which plate or blade is actuated by a spring 40 at one end and 80 by a lever 41 fixed at the other end, as shown in Figs. 2, 3 and 4.

The cam 42 is fitted with a toothed wheel 42^a similar to another toothed wheel 42^b fixed on the shaft 4 and is set in motion by 85 the said shaft by means of a chain as shown in Fig. 2. Said cam on striking the lever 41 rotates the plate or blade 39 and holds it in the position shown in Figs. 4 and 6, to allow the asphalt to be emptied in front 90 of the inlet orifice of the mold. A switchboard 44 is fitted with an ammeter and a voltmeter or a wattmeter to indicate the power consumed by the motor, as shown in Fig. 1.

A platform 43 forms the seat for the conductor who operates the machine and controls all driving means, viz: the rheostat 30, the toothed lever 29 for regulating the distribution of the asphalt, the switchboard 100 44 indicating the power consumed at each compression and the lever 20 serving to increase or diminish the pressure in the mold, the transverse iron wires, the rolls for the longitudinal iron wires, and the hopper for 105 the asphalt powder, as shown in Fig. 1. Another platform 46 permits of refilling the hopper 21 with asphalt powder.

The hopper 21 is fitted with two inclosing chambers 54, 55 while the pipes bordering 110 upon the latter, are fitted with gas burners 66, 67 which serve to heat this portion of the apparatus.

The distribution cylinder 22 likewise is hollow and incloses a pipe with burners 68. 115

A reservoir 56 containing compressed gas is suspended from the end of the carriage and through the intermediary of a conduit communicates with the pipes hereinbefore referred to.

A plate 57 of sheet iron forms an extension of the machine and serves as support for the asphalt as it is discharged from the compression mold, as shown in Figs. 1-4.

In some cases when very large surfaces or 125 long roads are to be paved, the machine or press may be built to be portable to produce the compressed asphalt strip on the spot where it is to be employed. Means are then also provided for allowing the strip to be de- 130

posed on the road direct from the machine as it is being turned out and for the machine to automatically move backward at the same rate the strip is being produced.

5 Such a machine is shown in Figs. 1 to 4 and comprises in addition to those already enumerated, the following parts:

Four wheels 60—47 which support the frame are mounted on rails 61 facilitating 10 the displacement and the automatic movement of the machine. The front wheels 47 are mounted upon fork like supports 62 fixed to a vertical axle, thus allowing of imparting a turning movement to them. The 15 supports 62 are fitted with worm wheels 48 driven by a screw axle 49, which is rendered operative with the aid of a crank handle and permits of turning the vehicle to change the direction as shown in Figs. 1 and 2. The 20 rear axle supports the wheels 60 mounted thereon. To the end of this axle is fixed a toothed wheel 63.

A drum or cylinder 51, the axle of which is supported by two arms 52 and two screws 25 53, presses against the strip of asphalt produced by the machine and by means of a gear 64 and chain 65 transmits its movement to the toothed wheel 63 of the rear axle 50, as shown in Figs. 1, 2, 3 and 4.

30 The rings 53^a of the screws 53 are made of caoutchouc so that the pressure of the latter be more constant.

The machine or press is started as follows:—

35 According to the thickness of the strip or slabs to be manufactured, the required additional distance pieces 11 are inserted between the top or cover plate 9 and the bottom plate or base 8 of the compression mold and the screw bolts O are then firmly 40 screwed fast. A compressing piston 7 of the corresponding thickness is bolted on the reciprocating carriage 6 and the piston guide 38 accurately adjusted to said piston.

45 The rolls of longitudinal wires, rope, cat-gut or the like, are placed on the magazine carrier 35 and their ends passed under the pulleys 36 and over the pulleys 37, under the piston guide 38 and through the wire guiding channels ending in holes, with which the compressing piston 7 is provided, as shown in Fig. 4. The wires diverging from the said piston are conveniently attached to a plank of hard wood placed in front of the 50 inlet orifice of the compression mold and ready to be forced into same by the first forward stroke of the compressing piston 7. The plank must be slightly thicker than the strip or slabs of compressed asphalt to be 55 produced.

60 Wires are then placed in the transverse wire magazine 31 to feed the wire distributer 32, as shown in Figs. 1 to 4.

The gas burners 66—67 of the inclosing 65 chambers of the hopper and those 68 of

the inner cavity of the distributer 22 are then lighted in such a manner, as to obtain, before starting the machine, a sufficiently high temperature to prevent the cooling of the asphalt powder, as shown in 70 Fig. 4. The asphalt powder as prepared in the ordinary way in asphalt boilers, is let into the hopper while still warm.

The machine or press works in the following manner: 75

The conductor or operator of the machine starts the electric motor 2, which by means of gearing drives the crank shaft 4 at a speed of say 15 to 20 revolutions per minute which, in its turn and by means of the connecting rods 5 and reciprocating carriage 6, to which is firmly bolted the compressing piston 7, drives said piston at equal number of strokes. At the first forward stroke, the 80 plank of hard wood M is forced into the mold and jammed or wedged between the walls or faces thereof.

To introduce the powder, the conductor pulls the toothed lever 29 toward him with the result that said lever disengages the pawl 90 24^a and thus enables the latter to run its full course.

At each turn of the crank shaft and during the backstroke of the compressing piston, the rotating arm 27 strikes the bell 95 crank arm 26 which actuates, by means of the rod 25, the ratchet and pawl 24 and 24^a, thus turning the grooved asphalt feeding cylinder 22 to the extent of four grooves. Said cylinder, in turning and being connected by the gear wheels 58 and 59 (Fig. 2) to the shaft fitted with blades 22^a causes the latter also to rotate. The blades thus engaging in the grooves, remove the asphalt powder from said four grooves and empty the 100 powder into the space between the inlet orifice of the compression mold and the compressing piston, the powder flattening plate or blade 39 being held in the position shown in Fig. 4 by the cam 42 shown in Fig. 2.

110 The cam is so set that during the forward stroke of the piston said cam releases the lever 41 fixed to the flattening plate or blade 39 which, actuated by a spring 40, drops and flattens down the asphalt powder emptied from the grooves of the distributing or feeding cylinder and holds said powder in place (Figs. 2 and 3).

115 The piston 7 in its forward stroke pushes the above said asphalt powder into the compression mold, compresses it against the plank of hard wood M already forced into said mold (Figs. 4 and 6) until the resistance opposed by said plank is overcome, and the said plank together with the mass of 120 compressed asphalt forced farther into the mold. At each piston stroke the operation is repeated.

125 The longitudinal wires are carried along with the wooden plank and thus advance 130

with it and remain embedded in the mass of compressed asphalt. At every forward stroke of the piston, the transverse wire distributor 32 advances to the extent of one notch, said notch carrying therein a wire, the length of which corresponds to the width of the mold. When the carriage advances, the inclined plane 34 operates a lever having a pawl mounted thereon, which engages in 10 the notch or teeth in the wire distributor and rotates the same.

From this it follows that at every forward stroke of the piston a wire is dropped into the chute 69, drops on to the piston and is placed behind the blade 39, as shown in 15 Figs. 4-5.

When the piston returns, the wire falls owing to gravity, upon the longitudinal wires and when the piston advances again, it 20 pushes this wire forward together with the asphalt powder, where the wire remains embedded at the moment of compression.

After a series of piston strokes, the mold will be completely filled with a mass of compressed asphalt reinforced with longitudinal and transverse wires, and, as the production goes on, said mass will be discharged at the outlet orifice of said mold in the form of a 25 strip of reinforced compressed asphalt.

Since the wooden plank M merely serves 30 the purpose of offering an initial resistance to the mass of asphalt for starting the operation, it may be removed by cutting the ends of the wires as soon as the compressed asphalt appears at the discharging end of the mold.

When the strip of compressed asphalt turned out has attained the required length, the supply or feed of asphalt powder is 40 stopped by pushing the lever 29 right forward. The continuity of the strip is maintained by interposing a ruler or flat bar of iron or any other hard material, having the same width and thickness as the piston and 45 provided with so many wire guiding channels as there are longitudinal wires, as shown in Fig. 9. Said flat bar is pushed into the mold by the first following forward stroke of the piston. The supply or feed is then re- 50 started by pulling back the lever 29 and the production of the strip or slabs continued.

When the ruler or flat bar, which is pushed along through the mold with the compressed asphalt, appears at the discharging end of said mold it is removed and the wires cut.

The feed is graduated by the lever 29, each position of which corresponding to a 55 definite course of the pawl 24 and rotation of the distributing or feeding cylinder 22 and therefore also to a definite supply of asphalt. When the lever is pushed right forward the feed is stopped and when pulled right back, as shown in Fig. 1, the 60 supply is maximum.

In the above first position the small lever 29^a mounted upon the axle of the lever 29 engages the extension 41^a of lever 41 of the powder flattening plate or blade 39 and the latter is arrested, (see Fig. 2).

At the start, the strip of asphalt may turn out either insufficiently or excessively compressed. It is however, of utmost importance that the compression of the asphalt strip or slabs be absolutely uniform and 75 that said compression be graduated at will, to any hardness required. This most important problem is resolved by the rocking plate 10 which constitutes a most essential part of the compression mold. A detailed 80 description of the working of said rocking plate is given below.

The rocking plate 10 is capable of a slight rocking movement that is imparted thereto at will, with the aid of a lever 20, as shown 85 in Figs. 1, 4 and 6. Said plate may assume various positions more or less parallel to the plane of the lower plate 8. If tilted downward, the friction of the compressed mass against the walls of the mold increases, 90 thus rendering the sliding movement or passage of the mass more difficult. Said mass therefore is more compressed and its hardness increased.

Vice versa, if the plate is tilted upward 95 the outlet orifice between the upper plate and lower plate is increased with the result that the compressed mass will slide more easily, while the necessary pressure as well as the hardness of the compressed mass will 100 be less. From this it follows that by moving the plate 10 the pressure exerted upon the mass may be increased or diminished at will, this movement being effected as follows:

The conductor observes on the wattmeter at the moment of maximum resistance the consumption of energy necessary for each piston stroke. The conductor therefore is capable of controlling whether this consumption corresponds to the work to be 110 done.

Should the consumption of energy be too small it suffices to lower the lever 20 for a few moments only, causing the plate 10 to tilt downward thus immediately increasing the pressure upon the mass, which increase and at the same time the increased pressure will be indicated on the wattmeter by an increased consumption of energy.

Vice versa, if the consumption is excessive and the mass is compressed excessively, the conductor will raise the lever 20 and thus tilt the plate upward with the result that the outlet orifice for the mass will increase and the pressure diminish, which will be indicated on the wattmeter by a decreased consumption of energy.

By means of this machine not only even surfaces that are adopted in the majority of 130

cases, but also ribbed, curved or the like surfaces may be obtained. To this end it is merely necessary to employ molds of the desired shape, provided the cross section is 5 always the same at all points of its length, with the exception of the small beveled and curved part of the rocking plate 10 at the entrance of the mold, when it is parallel to the plate 8 and a compression piston of the 10 desired form.

The beveled portion of the end of the plate serves the purpose of always maintaining during the movements of the rocking plate, the same distance between this plate and the 15 lower plate 8, thus allowing for the passage of the piston under the rocking plate.

Having now fully described my invention what I desire to secure by Letters Patent is:—

20 1. A machine for manufacturing bituminous material in form suitable for road paving or like purposes comprising a compression mold for compressing the bituminous material, a charger associated with the mold, 25 means for heating the material, inlet and outlet orifices to said mold, means for forcing the material through the mold, and means for increasing or diminishing the freedom of passage of the material through 30 the mold in order to vary the degree of consolidation of the resulting mass of material when it leaves the mold.

2. A machine for manufacturing bituminous material in form suitable for road paving or like purposes comprising a compression mold for compressing the bituminous material, a charger associated with the mold, means for heating the material, inlet and outlet orifices to said mold, a rocking plate 40 in said mold, means for forcing the material past the rocking plate out of the mold, and means for adjusting said plate in order to increase or diminish the freedom of passage of the material through the mold in order 45 to vary the degree of consolidation of the resulting mass of material when it leaves the mold.

3. A machine for manufacturing bituminous material in form suitable for road paving or the like purposes comprising a charger, heating means for the material, a compression mold for compressing the bituminous material and a compressing piston fitting into the cavity of said mold which 50 works with an alternative forward and backward movement, said compressing piston being adapted to push the bituminous material in the form of powder or the like material into the mold and compress the 55 said powder against the mass of compressed powder already contained in the said mold after overcoming the opposing resistance of said mass caused by its friction against the walls of the mold.

65 4. A machine for manufacturing bitumi-

nous material in form suitable for road paving and the like purposes comprising a charger, heating means for the material, a compression mold for compressing the bituminous material and a compressing piston 70 adapted to operate in said mold and apertures in said piston for the passage of reinforcing wires or the like therethrough said wires or the like constituting a longitudinal reinforcement for the mass of material produced in the mold. 75

5. A machine for manufacturing bituminous material in form suitable for road paving and the like purposes comprising a charger, heating means for the material, a compression mold for compressing the bituminous material, a compressing piston adapted to operate in said mold and means for supplying reinforcing members to the 80 mold cavity while the piston is in operation. 85

6. A machine for manufacturing bituminous material in form suitable for road paving and the like purposes, comprising a charger, heating means for the material, a compression mold for compressing the bituminous material, a compressing piston adapted to operate in said mold, to force the material through the mold, feeding means in the charger, and means for varying the rate 90 of feed of the material to said mold according to requirements. 95

7. In a machine for manufacturing bituminous material in form suitable for road paving and like purposes, the combination with a mold in which material in powdered form 100 is compressed, of a distributing cylinder for feeding the material and a shaft fitted with blades which blades engage in grooves in the distributing cylinder thereby removing the powdered material from the grooves and 105 emptying the powder into the inlet orifice of the compression mold.

8. In a machine for manufacturing bituminous material in form suitable for road paving and like purposes, the combination with 110 a heated distributing cylinder, of a shaft fitted with blades, which blades engage in grooves in said cylinder for receiving the material to be deposited into the inlet orifice of the compression mold, a toothed lever for regulating the distribution of the material and an automatically operated blade for flattening the material deposited in the inlet orifice of the mold before the material is pushed into the mold by the compressing 115 piston. 120

9. In a machine for manufacturing bituminous material in form suitable for road paving and like purposes, the combination with a mold for compressing the material, having 125 free inlet and outlet orifices, of a rocking plate for increasing and diminishing at will the outlet orifice for the material and therefore to increase and diminish the difficulty of the discharge of the material, a piston for 130

compressing the material in the cavity of the mold, actuating means for the piston which provide an alternative forward and backward movement thereof and serving the purpose of introducing the material to the inlet cavity of the mold, and also to press the material against the mass already contained in the mold to such an extent as to overcome the resistance of said mass, and a motor for 10 moving the compressing piston and mechanisms for regulating and distributing the feed of the material through a hopper to the mold, which also serves to operate adjusting means for varying the inclination of the 15 rocking plate with regard to the base of the

mold and to obtain a piece of paving material of predetermined thickness, means for introducing into the bituminous material longitudinal and transverse reinforcing material, and means for causing a backward 20 movement of the machine proportional to the discharge of material from the mold.

In testimony whereof I have signed my name to this specification in the presence of two subscribing witnesses.

JUAN MUGICA.
